APPARATUS FOR DISPENSING AND INSERTING HOOKS IN DRAPES AND THE LIKE

Morris A. Saltz, Los Angeles, Calif.

Application November 4, 1957, Serial No. 694,296

20 Claims. (Cl. 1-1)

The present invention relates to improvements in apparatus for inserting hooks in drapes, curtains, or similar flexible articles, that are to be hung by the hooks from a suitable support.

This application is copending with my application Serial No. 548,502, filed November 22, 1955, entitled Drapery Hook Dispensing and Inserting Apparatus, now Patent No. 2,821,713.

A general object of the present invention is to provide an improved apparatus of the character referred to for inserting drapery hooks into drapes, and like fabric articles, in a more effective and simple manner than possible, with previously available apparatus.

An object of the invention is to provide an apparatus that feeds drapery hooks from a stack or supply to a position where the said hooks are ready for inserting into the drapery, at any desired locations, as circumstances require.

Another object of the invention is to provide an apparatus that receives drapery hooks and is adapted to advance the hook in order to position the point thereof where it can be manually inserted into the drapery material, and which then operates to feed the hook into, along and through the drapery, to insure secure attachment of the hook to the drapery.

A further object of the invention is to provide a guide in an apparatus of the character referred to that positions the material of the drape so that the seam thereof is disposed adjacent to the plane of the hook to be inserted therein, to the end that the hook will not follow the line of stitching at the seam of the drape, which might otherwise weaken the same.

Yet another object of the invention is to provide an apparatus for dispensing and inserting hooks into drapes and the like, and embodying means for gripping each individual hook when it is positioned to be initially inserted into the drape, and as it is advanced into the drape, and which means is operated to unclamp the hook upon complete insertion into the drape.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such description is not to be taken in a limiting sense, since the scope of the invention is best defined by the appended claims.

Referring to the drawings:

Figure 1 is a top plan view of a portion of an apparatus embodying the invention;

Fig. 2 is a front elevational view of the apparatus taken along line 2-2 on Fig. 1;

Fig. 3 is a fragmentary sectional view taken along line 3-3 on Fig. 2;

Fig. 4 is a view similar to Fig. 3 and showing a drapery in position on the apparatus ready to have the drapery hook inserted therein;

Fig. 5 is a detailed sectional view taken along line 5-5 on Fig. 2;

Fig. 6 is a somewhat diagrammatic top plan view of a portion of the apparatus showing the drive plate

2

at the position where the point of the hook will be projected to be initially engaged in the drapery material;

Fig. 7 is a view similar to Fig. 6 showing the drive plate in a retracted position where it receives the drapery hooks from the supply thereof;

Fig. 8 is a view similar to Figs. 6 and 7 and showing the drive plate at its extreme forward position where the drapery hook is completely inserted into the material of the drapery;

Fig. 9 is a detailed sectional view taken along line 9-9 on Fig. 6 and showing the motor and drive that operates the apparatus.

The apparatus disclosed in the drawings is designed to receive a drapery hook from a suitable supply and move the pin portion thereof to a position where the fabric of the drape, or the like, can be inserted into the point, insuring the positioning of the drape in proper relation to the drapery hook. The drapery hook is then fed along the drape to insert the point thereof within

the fabric of the drape, preferably with the point of the hook avoiding the line of stitching along the seam of the drape. As a result, the weight of the drape will not be carried through the line of stitching, but through the material of the drape itself. The apparatus also positively holds the drapery pin hook during the period of driving it in and along the drape.

As specifically shown, each drapery hook 10 that is to be dispensed by the machine and inserted in the drape includes the pin portion 11 terminating in a forward point 12, the other end of the pin portion 11 merging into a curved web 13 which, in turn, merges into an inner arm 14 extending generally parallel to the pin portion 11. The outer portion 15 of the inner arm is bent outwardly at an angle, being inclined in a forward direction away from the pin portion. This bent arm portion 15, in turn, merges into a rearwardly and outwardly bent portion 16 of an outer arm 17, the rearwardly projecting portion of which is generally parallel to the inner arm 14 of the hook itself. In effect, the two inclined inner and outer arm portions 15, 16 form a general V shape, in order that the drapery hook may be suspended from and carried by a suitable hanger (not shown), in a known manner.

The drapery hook 10 is adapted to be received within a slotted and recessed portion of a drive plate 18, which is slidably mounted upon an upper supporting plate 19 of the frame of the apparatus, this upper supporting plate being suitably secured to the vertical walls 20 of the housing frame, which encloses the drive mechanism. A top plate 21 is carried by the upper supporting plate 19 of the frame in spaced relation thereto, the distance between the two plates 19, 21 being slightly greater than the thickness of the hook drive plate 18, so they will appropriately guide and confine the latter during its sliding movement therebetween. The appropriate spacing between the top plate and the supporting plate 19 is provided by spacer rings 22 disposed therebetween, the two plates being secured together by means of screws 23 extending through the top plate 21 and threaded within suitable holes in the supporting plate 19.

The drive plate 18 is adapted to be shifted to a rearward position in alignment with a supply of hooks 10, which are carried above the top plate 21, preferably by a suitable holder 24. The hooks 10 are appropriately arranged by the holder in the manner described specifically hereinbelow, being adapted to move singly from the lower end thereof, through an opening 25 in the top plate, into the slotted recess portion at the forward corner portion of the drive plate 18, which is designed to snugly accommodate a hook. Thus, the plate has a recess 26 in its front margin to receive the pin and inner arm portions 11, 14 of the hook, the recess being en-

larged in an inward direction to accommodate the curved web portion 13 of the hook. The plate is further cut out to provide an inclined edge 27 conforming to the inclined portion 15 of the inner arm, this edge 27 terminating at an inclined slot 28 which conforms generally to the inclination of the inclined portion 16 of the outer arm 17 of the hook, this inclined slot merging into an inner slot portion 29 that is generally parallel to the front edge 30 of the plate, and which is designed to accommodate the straight portion of the outer arm 17. In effect, the recess and slot portions 26, 28, 29 define a driving dog or lug 31 of the plate having forward tapered sides 27, 32 adapted to engage the inclined portions 15, 16 of the hook, in order to effect a coupling of the hook 10 to the plate 18, whereby the hook can be driven in a forward direction by the plate.

The driving plate 18 is disposed at the front portion of the top plate 21, and is guided along a predetermined path by a cam slot device 33 formed in the supporting plate 19 of the frame. The plate 18 has a pair of spaced pins 34, 35 depending therefrom and adapted to be received in the cam slot 33. The pins have a diameter substantially equal to the width of the slot, so that the shape of the slot 33 produces a corresponding movement of the drive plate 18 and of the hook 10 coupled thereto. The cam slot has a rearward portion 36 inclined in a rearward direction away from the front of the machine. When the plate is shifted in a rearward direction, the pins 34, 35 will ride rearwardly in the slot and when the rear pin 34 engages the rear slot portion 36, it will angle the plate 18 to the position disclosed in Fig. 7, wherein the pin receiving portion 26, 28 of the plate is disposed under the opening 25 and the supply of pins 10. Some part of the plate 18 at all times lies under the opening 25 in the top plate 21 of the apparatus, and it is only when the slot and recess portion 26, 28 of the plate is disposed under the opening that a hook 10 can drop thereinto from the vertical stack or supply of hooks arranged by the holder 24. The drive plate 18 is substantially the same thickness as a hook 10, in order that the hook can slide along and between the top plate 21 and the supporting plate 19 of the machine.

The rearwardly curved cam slot portion 36 merges into a substantially straight slot portion 37 that is generally parallel to the front edge 21a of the top plate. As the pin drive plate 18 is moved in a forward direction from the position shown in Fig. 7, it will carry the pin 11 in a forward direction, the point 12 of the pin being disposed at a substantial angle to the front edge 21a of the machine and ready for insertion in any drape or other material disposed in the plane of the pin (see plate 18 position in Fig. 6). As the plate 18 continues to move in a forward direction, it will advance the point 12 of the pin through the fabric, whereupon the forward pin or follower 35 will ride along the relatively straight slot portion 37, the rear pin or follower 34 moving from the rear curved slot portion 36 toward and into the straight slot portion, in order to dispose the pin 11 substantially parallel to the fabric of the material, the plate 18 then occupying the position shown in Fig. 8. When in this position, the pin 11 has completed its forward motion and the hook is disposed in alignment with an opening 39 in the top plate 21 of the apparatus, which will enable the hook to be lifted upwardly by the operator out of the drive plate 18 and the apparatus.

In accordance with the present invention, a clamp plate 70 is provided to hold or retain the hook 10 properly engaged with the plate 18, and to release the hook after it is fully inserted within the drapery material. In practice, the drive plate 18 has a back edge 71 parallel with the front edge 30 thereof and there is a drive slot 72 entering the plate at the back edge 71. The drive plate 70 is preferably located near the pin 34, there being a finger or lug 73 projecting from the plate 70 and entering the slot 72. The clamp plate 70 is carried

on a pivot 74 on an axis spaced laterally of the back edge 71 of the drive plate, said lug 73 and slot 72 being shaped to allow for the above-mentioned movement of the plate 18 and to provide driving connection between the drive plate 18 and a clamp plate 70. An arm 75 extends from the clamp plate 70 to overlie the forward edge 76 of the plate 18, being disposed opposite the tapered sides 27, 32 of the recess in the plate 18. As clearly shown in Fig. 1 of the drawings, the end portion of the arm 75 engages the hook 10 carried in the recess to clamp or hold the hook therein in engagement with the side 27, 32. As hereinabove described, the hook 10 has outer arm portions 15, 16 forming a V shape, and said portions are joined by a rounded or curved portion. This latter rounded or curved portion is engaged by a concave indentation 77 in the outer end portion of the arm 75 to hold the hook. As shown, the parts of the structure are so related that the clamp plate 70 engages the hook when the pin 11 is carried to the position where it is disposed to project somewhat from the front edge 21a of the machine (Fig. 1). However, when the slot and recess portion 26, 28 of the plate 18 is disposed under the opening 25 in the top plate 21 and when the plate has completed its forward motion, the clamp plate 70 is released, as shown in Figs. 7 and 8, respectively. Thus, the hook 10 is allowed to drop freely into the recess portion 26, 28 when the parts are positioned as shown in Fig. 7, the hook is clamped or held and retained in the recess portion 26, 28 when the parts are positioned as shown in Fig. 1, and the hook is released to be withdrawn through opening 39 when the parts are positioned as shown in Fig. 8.

In the apparatus specifically disposed, the drive plate 18 is moved by a power device. Thus, an electric motor 35 and a gear reducer unit 40 is carried by a supporting plate 41 disposed within the frame of the apparatus and suspended from the top supporting plate 19 of the frame by a plurality of bolts 42, the drive unit supporting plate 41 being spaced the appropriate distance below the frame supporting plate 19 by spacer sleeves 43 encompassing the bolts and extending between the plates. The vertical drive shaft 44 of the drive unit has a crank 45 affixed thereto to which a crankpin 46 is secured. This crankpin has one end of a connecting rod or link 47 pivotally secured thereto, the other end of the connecting rod being pivotally mounted on one of the pins, such as the forward pin or follower 35 attached to the drive plate 18.

As the drive shaft 44 is rotated by the drive unit 40, it will cause a reciprocation of the drive plate 18 through the agency of the crank 45, connecting rod 47 and the forward follower pin 35, the throw of the crank 45 being such as to move the plate between its full forward position disclosed in Fig. 8, and its rearward position disclosed in Fig. 7.

The electric circuit to the motor unit 40 is controlled by a suitable stop switch 38 and a suitable starting switch 48. The stop switch 38 is carried in any convenient manner within the apparatus, as by the drive unit supporting plate 41, while the starting switch 48 is at the exterior of the apparatus and preferably in the form of a treadle operated switch. The starting switch may have a suitable foot actuated member 49 operable to close the electrical circuit to the motor unit 40. The stop switch 38 has a button 50 projecting therefrom to be actuated by a leaf spring arm 51 secured to the switch itself and overlying the button 50, the arm extending into the path of travel of the crank 45. The crank has a projecting extension 52 secured thereto adapted to engage the free end of the arm 51, so as to actuate the stop button 50 to open the electrical circuit to the motor unit 40 and stop the apparatus when the drive plate 18 has shifted the pin point 12 of a hook just beyond the edge 21a of the machine (Fig. 1) where the point projects from said edge to be initially insertable into the drapery fabric by the operator.

The portion of the drape into which a hook is to be initially inserted is placed upon a platform or vertically movable supporting plate 54 disposed adjacent the front end of the apparatus, and below the plane of its top plate 21. This supporting plate 54 has a pair of generally vertical guide rods 55 secured thereto and depending therefrom, these guide rods being slidable through spaced upper and lower flanges 56 and 57 of a bracket 58 suitably secured to the front wall of the frame and housing 20. The supporting plate 54 is urged toward its uppermost position by helical compression springs 59 disposed around the guide rods 55, the lower ends of the springs engaging the upper flange 56 of the bracket and the upper ends of the springs engaging the underside of the supporting plate 54. It will be noted that the supporting plate 54 can be depressed against the force of the springs 59, and that the relieving of the depressing force will cause the spring to elevate the supporting plate to its uppermost position, as determined by engagement of the plate 54 with the guide 66 later described.

A gauge 61 is slidably mounted on the platform or supporting plate 54, in order that hooks may be inserted in various types and sizes of drapes at a predetermined point from their upper edges. This gauge includes, generally, a C-shaped element 62 having an opening 63 therein engageable over the plate 54, there being a thumb screw 64, or the like, threaded into part of the element 62 and engageable with the supporting plate 54. The gauge has a flat stop wall 65 disposed normal to the plate 54, against which the upper end of a drape can bear. By loosening the screw 64, the gauge 61 can be shifted along the supporting plate 54 to the desired position, depending upon the distance the hooks are to be inserted in the drape from its top edge. When the gauge 61 has been adjusted to the proper position, the screw 64 is retightened, to hold the gauge in such position.

The apparatus has a guide or indicator 66 (Figs. 3 and 4) to determine how far the operator must depress the supporting plate 54 to insure the insertion of a hook 10 at and through a drapery seam. This guide or indicator includes an arm 67 attached to and projecting from the front wall of the frame and housing, this arm terminating in an outwardly directed finger 68 disposed above or below the plane of movement of the drive plate 18 to project in a manner to be engaged with the seam of the drape (see Fig. 4). This outwardly directed finger is readily visible to the operator, who will place a portion of a drape on the supporting plate 54, and then exert a downward force on the drape until the supporting plate depresses to the extent at which the seam of the drape is in alignment with the finger 68 and the point 12 of the hook. In the particular form of the invention illustrated, the finger 68 is located just above the plane of the drive plate 18, and consequently above the plane and the hook 10. Thus, the seam will be located in an inclined position relative to the plane of movement of the hook, the point 12 of the hook 10 advancing through the line of stitching into the drapery material and within the material of the drape at one side of the seam or stitching. The pin of the hook is not extended along the line of stitching. Because of the initial projection of the point 12, as shown in Fig. 1 before the motor is started, the operator knows that the hook will be started through the drapery material at the proper location in the drape.

As stated above, a stack of hooks is supported vertically in a suitable holder 24, such as a plastic, paper or metal holder. The specific holder disclosed in the drawings is particularly set forth and claimed in my co-pending application Serial No. 694,326, filed November 4, 1957, entitled Drapery Pin Hook Package and Holder. The holder 24 serves as a means for storing a desired number of hooks 10 in proper stacked relation for sequential feeding into the recessed and slotted

portion 26, 28 of the drive plate, as they are needed. The holder 24, with a supply of hooks 10 arranged thereby, is suitably supported in vertical position on the apparatus within a receiver 82 attached to the top plate 21. This holder receiver 82 has a base portion 83 attached to the top plate 21 in any suitable manner, as by means of welding, for example, by spot-welding, and from which suitable guide walls project. The receiver 82 for the holder 24 includes a vertical guide wall 84 corresponding to the longer pin portion 11 of the hook 10, to engage and guide said portion of the holder 24. A guide channel 85 is provided at the point 12 of the hook 10, and a guide channel 86 is provided at the curved web 13 of the hook 10. As best illustrated in Fig. 1 of the drawings, the guide channel 85 is formed of walls 87 and 88, the wall 87 being at the forward portion of the wall 84, and disposed in spaced parallel relationship thereto. The wall 88 is disposed substantially at right angles to the walls 84 and 87, and is preferably a curved wall formed integrally with and joining the walls 84 and 87. The guide channel 86 is formed of walls 89 and 90, the wall 89 being at the rear portion of the wall 84, and disposed in spaced parallel relationship thereto. The wall 90 is disposed at right angles to the walls 84 and 89 and is preferably formed integrally with and joins the walls 84 and 89. The hooks 10 that are arranged in stacked formation by the holder 24 are allowed to feed downwardly in succession and into the drive plate slot and recess portions 26, 28 of the drive plate 18.

In the use of the apparatus described, the gauge 61 is adjusted to the appropriate position, the hook 10 being located in the Fig. 1 position illustrated in broken lines. The portion of the drape that is to have a hook inserted therewithin is placed on the top of the supporting plate 54, with its end disposed against the gauge wall 65. At this time, the plate 70 is clamped against the hook 10. The supporting plate 54 is then depressed against the force of the springs 59 until the seam of the drape is disposed in alignment with the indicator finger 68, the drapery material being initially inserted by the operator into the projecting point 12 of the hook. This initial engagement of the point 12 in the material of the drape at the seam insures that proper insertion of the hook at the correct location will be obtained. The starting switch 48 is then actuated through movement of the treadle 49, which will cause the drive plate 18 to be shifted to advance the hook 10 into the drapery material. The motor unit 40 drives the apparatus at a speed which allows the person sufficient time to lift the drapery and the inserted hook 10 from the apparatus after the hook 10 is brought into full alignment with the opening 39, the clamp 70 releasing from the hook (Fig. 8). However, the plate 18 does not stop until it reaches the position shown in Fig. 6. During its return travel to the Figs. 1 and 6 position, the cam slot 33 will turn the plate at an angle to the forward edge 21a of the top plate, disposing it under the supply of hooks 10 in the receiver 82. During such rearward movement of the plate, as well as during forward movement, it covers the opening 25 in the plate 21 and prevents hooks from dropping out of the receiver, until its slotted recess portion 26, 28 becomes aligned with the stack of hooks. When this occurs, the lowermost hook in the holder is dropped into the slot and recess portion, which can only accommodate a single hook. As the drive unit 40, crank 45 and connecting rod 47 continue to rotate, the plate 18 will then be driven in a forward direction to the position shown in Figs. 1 and 6, the point 12 of a new pin 11 projecting for initial insertion into the drape. When such position is reached, the extension 52 on the crank arm engages the stop button operating arm 51, actuating the switch to a circuit opening position and stopping the drive unit, which may, if desired, have a suitable magnetic brake incorporated therein to insure a rapid stopping of the apparatus. The

operator can then place the drape in a proper position on the supporting plate 54, depress the supporting plate to the proper extent with respect to the gauge finger 68 and pin point 12, initially insert the pin point 12 into the drapery material, and actuate the starting switch 48. The driving mechanism will again shift the plate 18 in a forward direction, advancing the pin 11 through the fabric of the drape adjacent its seam. After this has occurred, the plate is returned to its starting position at which the switch operating extension 52 on the crank member will engage the stop button operating arm 51, to again stop the drive mechanism, the parts occupying the position shown in Figs. 1 and 6. When in this latter position, another new hook 10 is again disposed with its point 12 projecting from the edge 12a of the top plate and is held in place by the clamp plate 70.

The foregoing cycle is then repeated as often as necessary to insert hooks into the drapes at the desired locations.

The hooks 10 are normally inserted at a seam of the pleated portion of the drape. However, it is not desired for the pin portion 11 of the hook to be disposed within and in alignment with the line of stitching at the seam, since such stitching may be torn. Instead, it is desired that the point 12 of the pin enter and be secured in place by the fabric of the drape itself. This is accomplished automatically in the apparatus disclosed in the drawings by simply positioning the supporting plate so that the stitching is in alignment with the indicator finger 68 and the point 12. Since the indicator finger 68 of the guide 66 is positioned just above or below, and preferably above, the plane of the drive plate 18 and the point 12, the line of stitching is inclined to the plane of movement of the hook 10. The pin portion 11 of the hook will penetrate and advance through the drapery material to one side of the stitching, but not along the stitching itself. After the point of the pin is forced into the drape D at the seam S, it will not travel along the seam under the stitching, but will be inserted into and within the fabric.

I claim:

1. In apparatus for inserting hooks in drapes and the like: a drive member adapted to receive a drapery hook having a pin portion; means operatively connected to said drive member to shift said drive member between a hook receiving position, a position in which the pin portion of the hook is inserted in the drape, and back to such hook receiving position; and means for clamping the hook to said drive member while said drive member is inserting the pin portion in the drape.

2. In apparatus for inserting hooks in drapes and the like: a drive member adapted to receive a drapery hook having a pin portion; means operatively connected to said drive member to shift said drive member between a hook receiving position, a position in which the pin portion of the hook is inserted in the drape, and back to such hook receiving position; and a releasable clamp member movable relatively to said drive member for clamping the hook to said drive member while said drive member is inserting the pin portion in the drape.

3. In apparatus for inserting hooks in drapes and the like: a drive member adapted to receive a drapery hook having a pin portion; means operatively connected to said drive member to shift said drive member between a hook receiving position, a position in which the pin portion of the hook is inserted in the drape, and back to such hook receiving position; and a releasable clamp member movable relatively to and operatively connected to said drive member for clamping the hook to said drive member while said drive member is inserting the pin portion in the drape.

4. In apparatus for inserting hooks in drapes and the like: a drive member adapted to receive a drapery hook having a pin portion; means operatively connected to said drive member to shift said drive member be-

tween a hook receiving position, a position in which the pin portion of the hook is inserted in the drape, and back to such hook receiving position; and a releasable clamp member movable relatively to and operatively connected to said drive member for clamping the hook to said drive member while said drive member is inserting the pin portion in the drape, said clamp member having an arm engageable with the hook to hold the hook tightly against the drive member.

5. In apparatus for inserting hooks in drapes and the like: a drive member adapted to receive a drapery hook having a pin portion; means operatively connected to said drive member to shift said drive member between a hook receiving position, a position in which the pin portion of the hook is inserted in the drape, and back to such hook receiving position; and a releasable clamp member movable relatively to said drive member, said clamp member having a lug received within a recess in said drive member to enable said drive member to actuate said clamp member, said clamp member having an arm engageable with the hook to hold the hook tightly against the drive member while said drive member is inserting the pin portion in the drape.

6. In apparatus for inserting hooks in drapes and the like: upper and lower guide members, one of said members having an opening therein through which hooks can move, the other of said members having a cam; a drive member having a recess to receive a drapery hook that has a pin portion; means on the drive member coacting with said cam to guide said drive member from a retracted hook receiving position in alignment with said opening to a position in which the pin portion of the hook is insertable into the drape; and a clamp member for holding the hook in the recess in the drive member while the drive member is inserting the pin portion in the drape.

7. In apparatus for inserting hooks in drapes and the like: upper and lower guide members, one of said members having an opening therein through which hooks can move, the other of said members having a cam; a drive member having a recess to receive a drapery hook that has a pin portion; means on the drive member coacting with said cam to guide said drive member from a retracted hook receiving position in alignment with said opening to a position in which the pin portion of the hook is insertable into the drape; and a releasable clamp member movable relatively to said drive member for holding the hook in the recess in the drive member while said drive member is inserting the pin portion in the drape.

8. In apparatus for inserting hooks in drapes and the like: upper and lower guide members, one of said members having an opening therein through which hooks can move, the other of said members having a cam; a drive member having a recess to receive a drapery hook that has a pin portion; means on the drive member coacting with said cam to guide said drive member from a retracted hook receiving position in alignment with said opening to a position in which the pin portion of the hook is insertable into the drape; and a releasable clamp member movable relatively to and operatively connected to said drive member for clamping the hook in the drive member while disposed in the recess therein and while the drive member is inserting the pin portion in the drape.

9. In apparatus for inserting hooks in drapes and the like: upper and lower guide members, one of said members having an opening therein through which hooks can move, the other of said members having a cam; a drive member having a recess to receive a drapery hook that has a pin portion; means on the drive member coacting with said cam to guide said drive member from a retracted hook receiving position in alignment with said opening to a position in which the pin portion of the hook is insertable into the drape; and a releasable clamp mem-

ber movable relatively to and operatively connected to said drive member for clamping the hook in the drive member while disposed in the recess therein and while the drive member is inserting the pin portion in the drape, said clamp member having an arm engageable with the hook to hold the hook tightly against the drive member.

10. In apparatus for inserting hooks in drapes and the like: upper and lower guide members, one of said members having an opening therein through which hooks can move, the other of said members having a cam; a drive member having a recess to receive a drapery hook that has a pin portion; means on the drive member coating with said cam to guide said drive member from a retracted hook receiving position in alignment with said opening to a position in which the pin portion of the hook is insertable into the drape; and a releasable clamp member movable relatively to said drive member, said clamp member having a lug received within a slot in said drive member to enable said drive member to actuate said clamp member, said clamp member having an arm engageable with the hook to hold the hook tightly against the drive member when disposed within said drive member recess and while said drive member is inserting the hook in the drape.

11. In apparatus for inserting hooks in drapes and the like: a drive member adapted to receive a drapery hook having a pin portion; means operatively connected to said drive member to shift said drive member between a first position to receive a hook, a second position at which insertion of the pin portion of the hook in the drape can commence, a third position in which the pin portion has been inserted in the drape, and back to such first position; and means for automatically stopping said drive member at said second position.

12. In apparatus for inserting hooks in drapes and the like: a shiftable support for a drape; a drive member adapted to receive a drapery hook having a pin portion; means operatively connected to said drive member to shift said drive member between a first position to receive a hook, a second position at which insertion of the pin portion of the hook in the drape can commence, a third position in which the pin portion has been inserted in the drape, and back to said first position; and means for automatically stopping said drive member at said second position, in order that the drape can be placed on said support and inserted in the pin portion of a hook with the drive member at said second position preparatory to starting of said drive member.

13. In apparatus for inserting hooks in drapes and the like: a drive member adapted to receive a drapery hook having a pin portion; means operatively connected to said drive member to shift said drive member between a first position to receive a hook, a second position at which insertion of the pin portion of the hook in the drape can commence, a third position in which the pin portion has been inserted in the drape, and back to said first position; an indicator adapted to receive the seam of a drape; said indicator and pin portion of the hook being offset from one another when said drive member and pin portion of the hook received therein are at said second position in order to dispose the drape seam at an angle to the direction of movement of the hook.

14. In apparatus for inserting hooks in drapes and the like: a drive member adapted to receive a drapery hook having a pin portion; means including an electric motor operatively connected to said drive member to shift said drive member between a first position to receive a hook, a second position at which insertion of the pin portion of the hook in the drape can commence, a third position in which the pin portion has been inserted in the drape, and back to such first position; and means for opening the circuit to said motor to stop said drive member at said second position.

15. In apparatus for inserting hooks in drapes and the like: a shiftable support for a drape; a drive member adapted to receive a drapery hook having a pin portion; means including an electric motor operatively connected to said drive member to shift said drive member between a first position to receive a hook, a second position at which insertion of the pin portion of the hook in the drape can commence, a third position in which the pin portion has been inserted in the drape, and back to such first position; and means for opening the circuit to said motor to stop said drive member at said second position, whereby the drape can be placed on said support and inserted in the pin portion of a hook while the driving member is at said second position and preparatory to restarting of said motor.

16. In apparatus for inserting hooks in drapes and the like: a drive member adapted to receive and be coupled to a drapery hook having a pin portion; means operatively connected to said drive member to shift said drive member between a rearward position from which the pin portion can be inserted into the drape and a forward position in which the pin portion is substantially fully disposed in the drape; and means for clamping the hook to said drive member while said drive member is inserting the pin portion in the drape.

17. In apparatus for inserting hooks in drapes and the like: a drive member adapted to receive and be coupled to a drapery hook having a pin portion; means operatively connected to said drive member to shift said drive member between a rearward position from which the pin portion can be inserted into the drape and a forward position in which the pin portion is substantially fully disposed in the drape; and a releasable clamp member movable relatively to said drive member for clamping the hook to said drive member while said drive member is inserting the pin portion in the drape.

18. In apparatus for inserting hooks in drapes and the like: a drive member adapted to receive and be coupled to a drapery hook having a pin portion; means operatively connected to said drive member to shift said drive member between a rearward position at which insertion of the pin portion of the hook in a drape can commence and a forward position in which the pin portion is substantially fully disposed in the drape; and means for automatically stopping said drive member at said rearward position.

19. In apparatus for inserting hooks in drapes and the like: a drive member adapted to receive and be coupled to a drapery hook having a pin portion; means operatively connected to said drive member to shift said drive member between a rearward position at which insertion of the pin portion of the hook in a drape can commence and a forward position in which the pin portion is substantially fully disposed in the drape; and spaced indicator means adapted to receive longitudinally separated portions of the seam of a drape for disposing the drape seam in a predetermined position relative to the drive member.

20. In apparatus for inserting hooks in drapes and the like: a drive member adapted to receive and be coupled to a drapery hook having a pin portion; means operatively connected to said drive member to shift said drive member between a rearward position at which insertion of the pin portion of the hook in a drape can commence and a forward position in which the pin portion is substantially fully disposed in the drape; and indicator means spaced longitudinally from the pin portion when the drive member is in said rearward position and adapted to receive the seam of a drape to locate the drape seam in a predetermined position relative to the drive member.
